DESIGN FOR A RADIO PROGRAM TIME INDICATOR

Edwin A. Canfield, Chatham, N. J.

Application November 2, 1943, Serial No. 111,572

Term of patent 7 years

To all whom it may concern:

Be it known that I, Edwin A. Canfield, a citizen of the United States, residing at Chatham, in the county of Morris and State of New Jersey, have invented a new, original, and ornamental Design for a Radio Program Time Indicator, of which the following is a specification, reference being had to the accompanying drawing, forming a part thereof.

In said drawing, Fig. 1 is a face view and Fig. 2 is a side edge view of a radio program time indicator embodying my new design.

I claim:

The ornamental design for a radio program time indicator, as shown.

EDWIN A. CANFIELD.
